Patented Aug. 29, 1922.

FIG. 1

FIG. 2

INVENTOR

H. J. CHAMPAGNE

ATTORNEY

Joseph J. O'Brien

UNITED STATES PATENT OFFICE.

HENRY J. CHAMPAGNE, OF PITTSFIELD, MASSACHUSETTS.

REMOVABLE HEEL.

1,427,261.

Specification of Letters Patent. Patented Aug. 29, 1922.

Application filed October 19, 1920. Serial No. 418,094.

To all whom it may concern:

Be it known that HENRY J. CHAMPAGNE, a citizen of the United States of America, residing at Pittsfield, in the county of Berkshire and State of Massachusetts, has invented certain new and useful Improvements in Removable Heels, of which the following is a specification.

This invention relates to improvements 10 in removable heels for shoes, boots and the like, and its leading object is to provide a heel which can be made of rubber composition or leather or other material, and which can be quickly removed when worn, 15 and replaced with a new heel without requiring the wearer to engage the services of a paid workman.

The invention is embodied in a heel construction which includes a detachable heel 20 member, having an internally threaded socket embedded therein, and a member secured by nails or the like to the heel lifts of the shoe, and provided with an externally threaded flange to enter the socket of the 25 detachable heel member, the two members being coupled together by a central screw which can be removed by a tool extended through the opening formed in the heel member.

With the above and other objects in view, 30 this invention relates to certain new and useful constructions, combinations and arrangements of parts, clearly described in the following specification, and fully illustrated in the accompanying drawings, in which:

Figure 1 is a vertical sectional view.

Fig. 2 is a top plan view.

Referring to the accompanying drawings 40 5 designates a shoe sole and 6 the heel lifts thereof. Against the lowermost lift 6 the inner attaching member 7 is secured by the nails or like means 8, which are driven through the openings provided in the central portion of the member 7 and the end wall thereof considerably clenched against the shoe sole in accordance with common practice. The central portion or end wall of the member 7 is provided with a centrally disposed socket 9 having internal screw threads, and the outer portion thereof is provided with a circular flange 10 having external screw threads thereon.

The detachable heel member 11 has embedded therein a socket member 12 having a circular flange 13 provided with internal

screw threads threaded on the flange 10, while the end wall of the socket member 12 is extended outwardly at 14 of the flange 13 so as to effectively interlock the socket member to the material of the heel 11. The socket member 12 is provided with a centrally disposed circular flange 15 having internal screw threads arranged in line with the internal screw threads of the socket 9. 65 The socket member 12 is embedded in the material of the heel 11 so that the outer edge portion of the circular flange 13 will be substantially flush with the upper face of the heel member 11, and the flange 13 is then 70 threaded on the flange 10 so that the confronting faces of the heel members 11 of the lowermost lift will be brought into snug contacting engagement. A screw plug 16 is then threaded through the central flange 75 15 and the socket 9, so as to bridge the joint between the flange 15 and said socket 9 and form a central positive connection between the inner and outer sections of the heel coupling. A left screw thread is provided on the circular flange 10 and right screw threads are provided on the screw plug 16 so that the heel member 11 will be absolutely locked against external rotative 80 movement. 85

By means of my invention a person can readily remove a worn heel and replace it with a new one by simply removing the central plug 16 which is provided with a screw slot 16^a, by inserting a suitable tool 90 in the opening 11^a, and then unscrewing the member 12 from the member 7.

Having described my invention, I claim:

1. A detachable heel for shoes or boots comprising a member adapted to be secured 95 against a lift and provided with an external flange having screw threads thereon, a detachable heel member having a circular flange embedded and interlocked thereto for screw threaded engagement with the first flange, each of said members being provided with registering flanges having screw threads therein and a screw plug threaded in said registering flanges, the threads of said registering flanges being of different 100 direction than the threads of the first flanges. 105

2. A detachable shoe heel comprising an inner member having a central socket provided with internal screw threads and a 110 flange surrounding said central socket provided with screw threads thereon, a socket

member having a flange to engage said circular flange and form screw threaded engagement therewith, and a portion projecting outwardly of said circular flange, a 5 detachable heel member in which said socket member is embedded, said detachable member having a central opening, said socket member having a central flange having screw threads therein, and a screw plug

threaded through said central flange and 10 said central openings and bridging a joint between the inner and outer members, the screw threads of said screw plug and the flanges engaged thereby, being of different direction than the screw threads of the 15 outer flanges.

Signed by me at Pittsfield, Mass.

HENRY J. CHAMPAGNE.
